CLAIM

The ornamental design for a towel holder hub, as shown and described.

DESCRIPTION

FIG. 1 is a perspective view of the towel holder hub showing a first environment, namely a towel holder having variable length and comprising the towel holder hub;
FIG. 2 is a perspective view of the towel holder hub of FIG. 1;
FIG. 3 is a front elevated view of the towel holder hub b of FIG. 1;
FIG. 4 is a back elevated view of the towel holder hub of FIG. 1;
FIG. 5 is a left side view of the towel holder hub of FIG. 1;
FIG. 6 is a right side view of the towel holder hub of FIG. 1;
FIG. 7 is a top view of the towel holder hub of FIG. 1;
FIG. 8 is a bottom view of the towel holder hub of FIG. 1;
FIG. 9 is a perspective view of the towel holder hub showing a second environment, namely a towel holder; and,
FIG. 10 is a perspective view of the towel holder hub showing a third environment, namely a towel holder.
The broken lines in the drawings are for the purpose of illustrating environment and form no part of the claimed design.

1 Claim, 5 Drawing Sheets
